SUSPENSION MEANS FOR PICTURE FRAMES

Edward N. Kellogg, Detroit, Mich.

Application June 5, 1937, Serial No. 146,602

1 Claim. (Cl. 248—29)

This invention relates to suspension means for picture frames and has particularly to do with means for hanging and maintaining picture frames in a true straight position.

Ordinary methods of picture or mirror hanging which comprise hanging the picture wire over a nail in the wall result in the picture becoming askew when it is accidentally jostled as by brushing against it or in dusting or cleaning the picture or the wall covered by the picture. The object of the present invention is to provide a means for suspending a picture or mirror so that it may always be readily placed in true position and such that it may be dusted or cleaned without disturbing its true position.

The invention is especially useful in art galleries where it is necessary that the picture be hung closely together and where it is especially desirable that none of them be aslant. Also in those areas which are frequently subject to earthquakes, the invention is desirable for picture hanging. Other uses for the invention are in hanging pictures in places where they are subject to strong draft or wind disturbances, or any stage scenery where it is essential that the picture be quickly adjusted to true position after the moving of the scenery into position on the stage.

Briefly, the objects of the invention are accomplished by providing a novel suspension device for an ordinary picture wire which is designed to remain where positioned on said wire, and by mounting a novel positioning member on the lower portion of the frame where it will engage a nail properly positioned in the wall.

35 In the drawing:

Fig. 1 shows a picture mounted on a wall, the various elements of the invention being shown in position in dotted lines.

Fig. 2 is an elevation of the back of a picture frame showing the relative positions of the various elements of the invention.

Fig. 3 shows a section of the wall taken through the center line of the picture mounted thereon.

Fig. 4 is a cross section of the lower positioning element of the picture frame showing its relation to the frame and the wall when in final position.

Fig. 5 illustrates a method of locating the position of a pin adapted to engage the lower positioning element of the frame.

Fig. 6 illustrates the manner in which the picture string or wire passes through the upper suspension device.

Referring to Fig. 2 the picture frame 8 is shown

55 in upright position with screw-eyes 9 positioned

in the usual fashion on the side members of the frame. A cord or wire 10 is fastened at each end on the screw-eyes 9. A triangularly shaped suspension member or bail 11 is provided with a central opening which has a notch at 12 to receive a nail or hook which is embedded in the wall. This notch 12 lies on the perpendicular bisecting line of the base of the triangle. The picture wire 10 is passed through holes 13 in the suspension member in a manner best illustrated in Fig. 6. 10 These holes 13 are located on the base of the triangle. It will be seen that the wire 10 is turned as it passes through the securing plate 11 at the points 14 so that when the member 11 is once positioned on the wire and the wire is subjected 15 to tension due to the weight of the picture there will be a binding effect between the wire and the member 11 which will prevent the member 11 from slipping from its original centered position 20 on the wire.

The centering means for the lower portion of the picture consists of a rectangular metal plate 15 positioned along the lower edge of the picture frame 8 by any convenient fastening means, as for example, the nails 16. The contour of 25 this metal plate is as shown in Fig. 4, it being provided with cam surfaces 17 on each side of an embossed or grooved portion 18. The cam surfaces 17 are formed to slope inwardly from the points 17a on the plate 15 to the groove portion 30 18. The plate 15 is to be exactly centered on the frame 8 so that the groove portion 18 falls on the vertical center line of the picture.

In hanging a picture with the device above described, the positioning plate 15 is tacked on to 35 the frame in the manner designated. The suspension member 11 is positioned on the wire 10 so that the notch 12 falls exactly on the center line of the picture. A pin or nail 19 is then driven into the wall at the point where the picture is 40 to be hung. A pin 20 is next driven into the wall directly beneath the suspending pin 19 and at such a distance therefrom that the positioning plate 15 on the picture frame will register with the pin 20. The proper location for the pin 20 45 can best be found by suspending a weight 21 from the top pin 19 as shown in Fig. 5. A point may then be marked on the wall which will register substantially with the positioning plate on the lower portion of the frame. When the picture 50 is hung by means of the suspension member 11 on the pin 19 the groove 18 of the plate 15 will engage the head of the pin 20 and the picture will then be exactly centered both at the top and bottom borders of the frame. The cam surfaces 55

17, due to the angle at which they are formed, serve to contact the pin 20 and guide the pin into the groove 18. The plate 15 will contact the wall at the points 17a and serve to space the lower 5 portion of the frame from the wall thereby lessening the amount of dust that normally collects behind pictures. The weight of the picture, whether it be small or large, is sufficient to maintain the groove 18 of the plate 15 in contact with the pin 20. It will be seen that the picture can be subjected to dusting or cleaning without disturbing its true position on the wall, and that any slight disturbances of the picture due to wind or dusting will be automatically corrected by 10 reason of the sloping cam surfaces 17. Furthermore, if it is desired to temporarily remove the picture from its position on the wall, it may easily be replaced in true position simply by hanging the member 11 on the top pin 19 and moving the 15 groove 18 into engagement with the pin 20. The 20 groove 18 into engagement with the pin 20. The

frictional engagement of the wire 10 with the member 11 will prevent it shifting from its centered position unless it is intentionally shifted.

What I claim is:

For use with a picture frame supported at the top by a suspending cord at each side of said frame and a bail frictionally engaging said cord, a centering device fastened at the lower portion of the picture comprising a sheet metal plate shaped to form a recess which is adapted to engage a pin extending from the wall upon which the picture is hung, spaced projections on said plate adapted to contact the wall on either side of said pin, said recess being positioned on the vertical center line of the picture, and cam surfaces on said plate sloping inwardly toward said recess from said spaced projections to automatically guide said pin to said recess. 10 15
